UNITED STATES PATENT OFFICE.

RICHARD A. HALEY, OF HOLLYWOOD, CALIFORNIA.

WINDING APPARATUS.

Application filed July 7, 1925. Serial No. 42,918.

To all whom it may concern:

Be it known that I, RICHARD A. HALEY, a citizen of the United States, residing at Hollywood, in the county of Los Angeles and State of California, have invented certain new and useful Improvements in Winding Apparatus, of which the following is a specification.

My invention relates to a winding apparatus primarily adapted for use in the laboratory in connection with the developing, washing, and drying of motion picture films.

One object of my invention is to produce a motor-driven mechanism wherein both hands of the operator may be free to handle the film.

Another object is to provide a construction driven by an electric motor having a rheostat in its circuit under control of a treadle switch, and a brake applicable by the treadle switch as it moves to open position.

A third object is to devise the apparatus in an inexpensive, simple, compact, unitary, and portable form capable of ready attachment to a support and to be controlled without undue interference with the normal use of the support.

The more specific objects and advantages will appear from a consideration of the following description taken in connection with the accompanying drawing illustrating one operative embodiment.

In said drawing:

Fig. 1 is a view of the device in side elevation as attached to a fragmentarily shown table;

Fig. 2 is a view of the parts of Fig. 1 taken at a right angle thereto; and

Fig. 3 is a diagram of the electrical connections.

Referring specifically to said drawings, 10 designates a conventional attaching bracket or base which may be generally of U-shape as shown, so that it may embrace the edge 45 portion of a table T or other support and be rigidly but removably secured thereto by set screws 11.

To an upper arm 12 of the attaching bracket 10, a winding mechanism W is mounted, having for instance a casing 13 detachably bolted thereto at 14. Mechanism W has a winding drum 15 carried by a rotatable shaft 16 adapted to be driven from a shaft 18 through intermediate gearing not shown.

Said shaft 18 is adapted to be driven by an electric motor 19 whose base is detachably bolted or otherwise fastened at 20 to a lower arm 21 of bracket 10. To this end a bevel gear 22 is keyed to the main shaft 23 of said motor and meshes with a bevel gear 24 on a vertical countershaft 25 to which a bevel gear 26 is fastened so as to mesh with a similar gear 27 keyed to the shaft 18. Shaft 25 may be journaled in a bearing 28 integral with bracket 10 and held therein against vertical displacement by collars 29 on said shaft.

The motor 19 is arranged under and in line with the winding mechanism and below the motor and in line with the same, and mechanism W is a rheostatic switch mechanism R for control of the motor. Specifically, this mechanism W has a base plate 30 adapted to be bolted to the floor at 31. On the base plate 30 is a box or casing 32 forming the rheostat proper in that it has resistance 33 therein and exterior contacts 34 therefor in proper insulated relation to the casing. Pivoted to the base plate 30 at 35 is a switch arm or treadle 36 carrying a contact 37 insulated therefrom and adapted for successive engagement with contacts 34 to throw more or less resistance into the motor circuit to govern its speed of operation. Arm 36 is normally maintained in and urged to the off position by an expansive spring 38 fastened between the pedal and the base.

The parts are shown in electrical diagram in Fig. 3 and with reference thereto, a usual plug 39 is adapted to be screwed into an electric socket. From the plug one conductor 40 leads to motor 19. A slack conductor 41 extends from the motor 19 to contact 37. Resistance 33 is connected to the plug 39 by a conductor 42. A switch 43 may be included in conductor 41 to be left open when the apparatus is not operating to prevent accidental operation through depression of treadle 36.

A brake rod 44 is vertically slidable in bearing 28 and has an arcuate shoe 45 adapted for normal braking engagement against the periphery of a drum 46 integral with or attached to gear 27. The rod 44 moves with the treadle 36 and is connected thereto by a pin 47 on the rod engaging an elongated slot 48 of the pedal. By means of this construction the arm 36 is urged to off position by spring 38 and such movement of the arm

applies the brake rod 44 at shoe 45 against drum 46 to arrest motion of the winding drum 15.

Said winding drum 15 preferably comprises a disk 48 and a hub lug or stub shaft 49.

The various conductors cannot be identified in Figs. 1 and 2 since they are conveniently grouped in insulation 50.

- 10 Presuming operation, plug 39 is attached to an appropriate socket such as an electric lamp socket and the operator places one foot on the treadle 36. With the electric current otherwise established, depression of treadle 36 engages the contact 37 with uppermost contact 34, thus starting the motor 19 at the slowest speed. Further depression causes contact 37 to successively engage the remaining contacts 34 to decrease the amount of resistance in circuit and thereby increase the speed of operation of the motor. As a result of the structure both hands of the operator are left free to control the material being wound.
- 15 Said motor 19 drives shaft 23, and the latter by means of gears 22 and 24 drives countershaft 25. Shaft 25, through gears 26 and 27, drives shaft 18, gearing 17, shaft 16 and drum 15. The material is wound around the stub shaft 49. To cease operation, the pressure of the foot on treadle 36 is released and spring 38 throws said treadle to the off position of Fig. 1, thus breaking the circuit to the motor 19. At
- 20 the same time, treadle 36 applies the brake rod 44 against drum 46 and arrests motion of the winding drum 15.
- 25 Said motor 19 drives shaft 23, and the latter by means of gears 22 and 24 drives countershaft 25. Shaft 25, through gears 26 and 27, drives shaft 18, gearing 17, shaft 16 and drum 15. The material is wound around the stub shaft 49. To cease operation, the pressure of the foot on treadle 36 is released and spring 38 throws said treadle to the off position of Fig. 1, thus breaking the circuit to the motor 19. At
- 30 the same time, treadle 36 applies the brake rod 44 against drum 46 and arrests motion of the winding drum 15.
- 35 The apparatus is particularly useful in the laboratory in connection with motion picture films, before they are placed on reels, and particularly in connection with

their development, washing and drying and formation into rolls. As one foot controls the motor and brake, both hands may engage the film. At the same time, it is to be realized that the compact and relatively attenuated arrangement of the elements avoids parts which hamper the operator or normal use of the table.

Various changes may be resorted to within the spirit and scope of my invention.

I claim:

1. A winding apparatus comprising a winding mechanism, an electric motor below the same, an attaching bracket for said mechanism and motor, a treadle switch for and below the motor, a driving connection from said motor to said mechanism and supported on said bracket, a drum forming a part of said connection, and a brake rod movable with said treadle switch disposed relatively close to said connection and engageable with said drum.

2. A winding apparatus comprising a winding mechanism, and electric motor substantially in line therewith below the same, an attaching bracket between and by which said mechanism and motor are carried, a bearing on said bracket, an upstanding countershaft journaled in said bearing, gearing to drive said countershaft from said motor, gearing to drive said mechanism from said countershaft including a drum, a base below the motor, a rheostat on said base, a switch arm pivoted to said base and coacting with the rheostat to control the motor circuit, a spring on said base urging the switch arm to off position, and a brake guided by said attaching bracket and connected to said switch arm for application against the drum through off movement of the switch arm.

RICHARD A. HALEY.
